UNITED STATES PATENT OFFICE.

WADDIE E. COOLEY AND BARNEY L. FERGUSON, OF HONEA PATH, SOUTH CAROLINA;
SAID WADDIE E. COOLEY ASSIGNOR TO EDGAR R. DONNELL AND SAMUEL F. DON-
NALD, BOTH OF HONEA PATH, SOUTH CAROLINA.

COMBINED CHECKSTRAP AND BINDER-SPRING HOLDER FOR LOOM LAY BEAMS.

Application filed February 25, 1926. Serial No. 90,593.

The invention relates to an attachment for loom lay beams that will support the picker check strap and also the binder spring for the shuttle box brake.

5 The usual construction of loom lay beams includes a bracket member carrying the check strap for the picker stick that is secured to the beam and also includes means for securing the binder spring for the shuttle box brake. Because of the jars to which the check strap bracket is subjected by the operation of the picker stick, the screw or bolt used to fasten the bracket to the lay beam eventually loosens and finally breaks 10 out so that repair of the lay beam is necessary, or a new beam installed.

This invention has for its object the provision of means by which a quick repair can be made and consists in the provision of 20 a bracket comprising a plate adapted to be secured to the side of the lay beam by the same screws that hold the binder spring on the beam and having a depending tongue on which the check strap is secured and a 25 laterally extending lug that is adapted to be secured under the lay beam by means of the bolt pivoting the shuttle box binder brake in the shuttle box. The outer face of the plate is formed with a depression 30 having an inclined lower wall to properly support the binder spring in position on the beam and the inner face of the depression is inclined from the outer edge of the plate to also properly position the binder spring. 35 The invention will be described in detail hereinafter and will be found illustrated in the accompanying drawings, in which—

Figure 1 is a side view in elevation of a lay beam showing the improved attachment in position,

Figure 2, a side view on an enlarged scale of one of the attachments,

Figure 3, an end view of Figure 2,

Figure 4, a top edge view, and

45 Figure 5, a vertical sectional view on a plane indicated by the line 5—5 of Figure 2.

In the drawings similar reference characters will be used to designate corresponding parts in the several views.

In Figure 1 of the drawings a lay beam is indicated at A having the usual rib B,

while C is a shuttle box at each end of the beam, and D the binder brake in each shuttle box, E indicating the binder spring carried by the lay beam. F is the picker check strap that is usually carried by the bracket, as hereinbefore described.

The improved check strap and binder spring holder comprises brackets that are 60 made in left and rights as shown in Figure 1 to fit the two ends of the lay beam, and each bracket comprises a plate 1 having a downwardly extending tongue 2 to which the check strap F is secured. The outer face 65 of the plate 1 is provided with a depressed portion 3 having an upwardly inclined lower wall 3^a while the inner face of the depression is inclined from the outer edge of the plate as clearly shown at 4 in Figure 70 4. The depression 2 is formed to receive the binder spring E and the inclined lower wall 3^a and inner face 4 is designed to properly position the spring so that its outer free end is in engagement with the 75 binder D.

The plate 1 is provided with openings 5 and 6 through the inner face of the depression 2 to receive screws or other suitable fastenings secured through the binder spring D to secure said binder spring and the plate to the loom lay. The bracket is also held in position by means of a laterally extending lug 7 having an opening 8 through which the bolt 9 forming the pivot bolt for the binder D is secured.

The inner face of the plate 1 is thickened 80 as shown at 10 and has its upper edge 11 curved to fit the contour of the rib B at the ends of the beam, this providing for a 90 snug fit of the bracket on the beam.

It will be understood that by using the bracket, hereinbefore described, the lay beam may be continued in use after the original bracket supporting the check strap 95 has been discarded because of the splitting of the lay beam as hereinbefore referred to, but it will also be understood that the bracket may be used as an original installation for lay beams and we do not therefore limit ourselves to use of the device as 100 a repair device only.

What is claimed is:—

1. An attachment for loom lay beams, in-

cluding a plate adapted to be secured to the side of a lay beam, means on said plate to support a check strap, and the plate having a depression therein to receive a shuttle box binder spring.

2. An attachment for loom lay beams, including a plate adapted to be secured to the side of a lay beam, means on said plate to support a check strap, the plate having a depression therein with an upwardly inclined lower wall, the inner face of said depression inclined from the outer edge of the plate towards the inner face thereof, said depression being adapted to receive a shuttle box binder spring, and the plate provided with openings through the base of the depression to receive fastenings for the

spring aforesaid and to secure the plate in position on the lay beam.

3. An attachment for loom lay beams, comprising a plate adapted to be secured to a lay beam, a downwardly extending tongue thereon to carry a check strap, a laterally extending lug adapted to engage under the lay beam, said plate being adapted to be secured to the beam by the fastenings for a shuttle box binder spring and having a depression to receive the ends of the spring, and the lug adapted to be secured by the shuttle box binder pivot bolt. 30

In testimony whereof we affix our signatures.

WADDIE E. COOLEY.
BARNEY L. FERGUSON.
